(57) **CLAIM**

The ornamental design for straps for a wearable device, as shown and described.

DESCRIPTION

FIG. 1 is a top perspective view of straps for a wearable device embodying our new design;

FIG. 2 is another top perspective view thereof;

FIG. 3 is a bottom perspective view thereof;

FIG. 4 is another bottom perspective view thereof;

FIG. 5 is top view thereof;

FIG. 6 is bottom view thereof;

FIG. 7 is front view thereof;

FIG. 8 is back view thereof;

FIG. 9 is side view thereof;

FIG. 10 is another side view thereof;

FIG. 11 is another perspective view thereof in an assembled state; and,

FIG. 12 is an enlarged perspective view of a portion of that which is shown in FIG. 1.

Broken lines, where shown, are used to illustrate portions of the straps for a wearable device that form no part of the claimed design.
